UNITED STATES PATENT OFFICE.

LOUIS FRED GRISWOLD AND CECIL BASS SMITH, OF CLEVELAND, OHIO; SAID GRISWOLD ASSIGNEE TO SAID SMITH.

ROTARY DRIER.

1,080,629.

Specification of Letters Patent.

Patented Dec. 9, 1913.

Application filed January 2, 1913. Serial No. 739,745.

To all whom it may concern:

Be it known that we, LOUIS FRED GRISWOLD and CECIL BASS SMITH, both citizens of the United States, and residents of Cleveland, in the county of Cuyahoga and State of Ohio, have jointly invented a new and useful Improvement in Rotary Driers, of which the following is a specification.

Our invention relates to direct heat rotary driers, for drying sand, cement, tankage, etc., and so far as our knowledge of the art extends, heretofore the most satisfactory driers of the class have been constructed with the drying cylinder set on an incline, and provided internally with lifting blades or other suitable means for cascading or agitating the material. The cylinders are inclined for the purpose of causing the material to gradually travel from the feed end to the discharge end of the cylinder. In order to obtain the desired result, of thoroughly drying the material, it has been necessary to make these cylinders from twenty to fifty feet in length, to retain the material in the cylinder a sufficient length of time to dry. The cost of driers of this construction, and the large amount of space which they occupy, confines their sale almost wholly to large plants whose owners have more or less extensive capital and makes them prohibitive to many would be users, who have small capital and limited floor space.

The objects of this invention are to provide a direct heat drier at a comparative low cost, that is simple and durable in construction, efficient in its operation, and compact and self-contained, making it easy to install, and adapting it to the requirements of small plants, without in the least reducing the efficiency or materially reducing the per diem capacity in the drying of material of certain qualities.

Another object of the invention is to provide means for feeding the material from the hopper to the drying cylinder, whereby the said material is subjected to beneficent effects of the heat, before it enters the cylinder.

A further object of the invention is the providing of means for tempering the gases entering the cylinder, whereby the temperature can be kept under perfect control, which is a very desirable factor in the drying of delicate material.

Still another object of the invention is to provide means for closing the gas inlet to the cylinder, and thereby causing the action of the suction draft to produce a partial vacuum within the cylinder, which expedites the drying of the material.

Other objects and advantages of the invention will be made apparent from the following specification, considered in connection with the accompanying drawings, in which—

Figure 1 is a longitudinal, vertical section through the complete apparatus, excepting the drying cylinder, which is shown with only a portion of the heads in section, and the suction fan being shown in outline elevation. Fig. 2 is an end view, partially in section on line 2, 2 of Fig. 1, and Fig. 3 is a fragmentary view illustrating a modified form of feeding means.

Throughout the drawings and specification, numerals are employed for designating the different coöperating accessories.

An important feature of the invention is the eccentric, oblique rotation of the cylinder, and while we are aware that this construction is old as applied to devices used for other purposes, it has not, to our knowledge, heretofore been applied and employed in the construction of direct heat driers, or used in combination with similar accessories to obtain the results produced by this invention.

The eccentric, oblique rotation of the cylinder, causes the material contained therein to be thrown about from end to end, and in all directions, thereby subjecting all parts of it to the heat imparted from the cylinder casing, and permitting the gases that enter the cylinder to commingle with, and pass through the disintegrated mass as it is agitated by the tumbling process.

Referring now to the drawings, 1 represents a housing which is superimposed relative to the furnace 2. The housing forms a chamber 100 which is in open communication with the furnace 2, through the openings 2^a in the furnace arch.

The drying cylinder 4 is closed at both ends by the heads 4^a and 4^b. A trunnion 5 is rigidly attached to the cylinder head 4^a, eccentric to the center line thereof, and a trunnion 6 is rigidly attached to the head 4^b, eccentric to the center line thereof, and obliquely to the trunnion 5. The trunnions 110

5 and 6 are mounted in suitable bearings 7 and 8, and the cylinder 4 inclosed within the housing 1, is revolved by power applied to one or the other of said trunnions. In the drawings this is provided for by a sprocket wheel 9, keyed or otherwise made fast to the trunnion 6, and driven by a suitable motor and sprocket chain, not shown.

The trunnion 5 is hollow, as shown in Fig. 1, and thereby provides an open passage 5^a, from the exterior of the housing 1 to the interior of the cylinder 4, the opening 4^a in the cylinder head 4^b, registering with the opening in the trunnion 5. A suction fan 10, or other suitable suction draft means is arranged in open connection with the passage 5^a.

The cylinder head 4^b is provided with an opening 4^c, and the trunnion 6 is provided with a chamber 6^a, with which the opening 4^a communicates. Gases from the chamber 3 pass through openings 6^b, into the chamber 6^a. A valve 11 is provided for opening and closing the opening 4^c.

It will be readily understood, that, when the valve 11 is open, the heated gases from the chamber 3 will be drawn by the suction fan 10 through the openings 6^b and 4^a, into the interior of the drying cylinder, and out through the passage 5^a. When the valve 11 is closed, the action of the suction fan will produce a partial vacuum in the drying cylinder, the advantage of which will hereinafter be mentioned.

A novel method of feeding the material into the drying cylinder is provided by a spiral conveyer 12, connected with, and operating in the hollow trunnion 5; this conveyer extends into a depending portion 13^a of the hopper 13. The material from the hopper 13 is carried by the conveyer 12 through the passage 5^a, into the cylinder 4, and is exposed to the heated gases being drawn by the suction fan, through the said passage, in the opposite direction. The material after being dried is discharged through an opening in the cylinder head 4^b, which is provided with a suitable closure member, adapted to be removed, and so constructed that it can be replaced and tightly locked during the rotation of the cylinder.

One or more openings 14 are provided in the housing 1, through which external air can be admitted to the chamber 3, and by commingling with the heated gases, reduce the temperature. The supply of air through the openings 14 is regulated and controlled by suitable dampers.

While the preferred manner of feeding the material to the drying cylinder, is through the hollow trunnion 5, the feed may be as shown in Fig. 3, through a hatch 15, in the housing 1, and a dome 16, provided with a suitable sealing cover 16^a.

In the operation of the improved drier,

the material is fed into the drying cylinder, to the extent of approximately one-third of the capacity of said cylinder. As the cylinder is rotated the material is agitated by being tumbled about in all directions. The gases from the furnace heat the shell of the cylinder, which imparts heat to the material contained therein. In the first stages of the operation of the apparatus, if the valve 11 is closed the drying effect of the heat from the cylinder shell is enhanced by the partial vacuum produced by the suction fan 10. After the material has been dried to a certain extent, which depends on the nature of the material, the valve 11 is opened and the heated gases pass through the cylinder and complete the drying process. If the temperature is found to be too high, it may be regulated by the dampers in the openings 14.

While we have, in this specification, described and shown an apparatus embodying the principles of our invention, we do not intend to be limited to this particular construction, only in so far as required by the scope of the claims, and the existing state of the art to which the apparatus appertains.

What we claim and desire to secure by Letters Patent is—

1. In a rotary drier, a drying cylinder adapted to rotate eccentrically and obliquely to the rotation of the driving member, whereby the material to be dried is agitated, in combination with means for drawing a heating and drying medium through the interior of said cylinder.

2. In a rotary drier, a drying cylinder adapted to rotate eccentrically and obliquely to the rotation of the driving member whereby the material to be dried is agitated, in combination with an opening or openings for admitting heat to the interior of said cylinder, suction means for drawing the heat through the interior of the cylinder, and means for closing the admission openings, whereby the suction means will cause a partial vacuum in said cylinder.

3. In a rotary drier, a drying cylinder adapted to rotate eccentrically and obliquely to the rotation of the driving member whereby the material to be dried is agitated in combination with an inclosing chamber in which said cylinder rotates, means for supplying heat to said chamber, means for drawing heat from the chamber through the interior of the cylinder, and means for admitting and regulating a supply of non heated, exterior air to the chamber whereby the temperature of the medium within said chamber and the cylinder is reduced.

4. In a rotary drier, the combination of a drying cylinder, an inclosing chamber in which said cylinder is adapted to rotate, trunnions eccentrically and obliquely attached to the two heads of said cylinder and mounted in suitable bearings, a longitudinal

opening in one of the trunnions and its attached cylinder head, suction draft means connected with the interior of the cylinder through the said opening, open communication from the chamber to the interior of the cylinder through the opposite trunnion and cylinder head, whereby heat from the chamber is drawn through the cylinder, means for feeding material to be dried to said cylinder, and means for discharging the dried material therefrom.

5. In a rotary drier, the combination of a drying cylinder, an inclosing chamber in which said cylinder is adapted to rotate, means for supplying heat to said chamber, a hollow trunnion eccentrically attached to one head of said cylinder, open communication from a suction draft means, through the hollow trunnion to the interior of the cylinder, means for feeding material to the interior of the cylinder through the said hollow trunnion, a trunnion attached eccentrically to the opposite head of the cylinder and in oblique relation to the first named trunnion, open communication from the chamber to the in-

terior of the cylinder through the last named cylinder head, and means for closing said opening.

6. In a rotary drier the combination of a drying cylinder; an inclosing chamber in 30 which said cylinder is adapted to rotate; means for supplying heat to said chamber; trunnions attached to the opposite heads of the drying cylinder and mounted in suitable bearings, whereby said cylinder is revolved; 35 a longitudinal opening in one of the trunnions and its attached cylinder head at the feed end; a spiral conveyer attached to the trunnion within said opening, whereby the material is fed to the interior of the cylinder 40 by the revolution of the trunnion; means for admitting heat from the chamber to the interior of the cylinder; and suction draft means connected with the cylinder at the feed end thereof.
